US0D1033428S

(12) **United States Design Patent** (10) **Patent No.:** **US D1,033,428 S**
(45) **Date of Patent:** **** Jul. 2, 2024**

(54) **ORGANIC WASTE APPLIANCE**

(71) Applicant: **TERO INNOVATION INC.**, Quebec (CA)

(72) Inventors: **Elizabeth Coulombe**, Quebec (CA); **Valerie Laliberte**, Val-D'Or (CA)

(73) Assignee: **Bigz Tech Inc.**

(**) Term: **15 Years**

(21) Appl. No.: **35/513,552**

(22) Filed: **Aug. 11, 2021**

(80) **Hague Agreement Data**

Int. Filing Date: **Jul. 16, 2021**

Int. Reg. No.: **DM/215818**

Int. Reg. Date: **Aug. 11, 2021**

Int. Reg. Pub. Date: **Feb. 11, 2022**

(51) **LOC (14) Cl.** **09-09**

(52) **U.S. CL.**

USPC **D34/9**

CLAIM

The ornamental design for an organic waste appliance, as shown and described.

DESCRIPTION

1.1: Top perspective view

1.2: Bottom perspective view

1.3: Front elevational view

1.4: Rear elevational view

1.5: Top plan view

1.6: Bottom plan view

1.7: Left side elevational view

1.8: Right side elevational view

3.1: Top perspective view

3.2: Bottom perspective view

3.3: Front elevational view

3.4: Rear elevational view

3.5: Top plan view

3.6: Bottom plan view

3.7: Left side elevational view

3.8: Right side elevational view

4.1: Top perspective view

4.2: Bottom perspective view

4.3: Front elevational view

4.4: Rear elevational view

4.5: Top plan view

4.6: Bottom plan view

4.7: Left side elevational view

4.8: Right side elevational view

The broken lines in the drawings illustrate portions of the organic waste appliance and form no part of the claimed design.

The unshaded surfaces bound on all sides by broken lines form no part of the claimed design.

1 Claim, 24 Drawing Sheets
